DESIGN FOR A RUG.

SPECIFICATION forming part of Design No. 35,251, dated October 29, 1901.

Application filed September 30, 1901. Serial No. 77,161. Term of patent 3½ years.

To all whom it may concern:

Be it known that I, ADOLPH PETZOLD, a citizen of the United States, residing at the city of Philadelphia, State of Pennsylvania, have 5 invented and produced a certain new and original Design for a Rug, of which the following is a full, clear, and exact description, reference being had to the accompanying drawing, forming a part of this specification.

My design is applicable to and intended for the surface ornamentation of woven rugs. In its essentials it consists, as shown in the drawing, of end border-lines *a a'* and side border-lines *b b'*, which are narrow and respectively 5 parallel. These lines are straight, except at their ends, which are curved inward in order

to give a rounded effect at the border-corners. The field center is composed of flowers and leaves *A*, arranged *en masse* at each end, and between them are two parallel-line figures *c* 20 and vine-like figures *d*, the inner center being filled with connected scroll-line figures *m*.

I claim—

The design for a rug substantially as shown and described.

In testimony whereof I have hereunto affixed my signature this 13th day of August, A. D. 1901.

ADOLPH PETZOLD.
